(57) **CLAIM**

The ornamental design for an interconnect enclosure for computer and audio visual equipment concealable in a table top, as shown and described.

DESCRIPTION

FIG. 1 is a perspective view of an interconnect enclosure for computer and audio visual equipment concealable in a table top in an open position, said perspective view showing a front view, a right side view and a top view thereof. The broken lines are to illustrate an environment only and form no part of the claimed design.

FIG. 2 is a perspective view thereof in a concealed position. The broken lines are to illustrate an environment only and form no part of the claimed design.

FIG. 3 is a front elevational view thereof in the open position. The broken lines are to illustrate an environment only and form no part of the claimed design; and,

FIG. 4 is a top plan view thereof in the concealed position. The broken lines are to illustrate an environment only and form no part of the claimed design.

The appearance of the bottom forms no part of the claimed design.
